UNITED STATES PATENT OFFICE.

WILLIAM BAYHOUSE, OF BOISE, IDAHO.

DESIGN FOR A HEEL-PLATE.

SPECIFICATION forming part of Design No. 27,630, dated September 7, 1897.

Application filed May 11, 1897. Serial No. 636,567. Term of patent 14 years.

To all whom it may concern:

Be it known that I, WILLIAM BAYHOUSE, a citizen of the United States, residing at Boise, in the county of Ada and State of Idaho, have 5 invented and produced a certain new and original Design for Heel-Plates; and I do declare the following to be a full, clear, and exact description of the invention, such as will enable others skilled in the art to which it 10 appertains to make and use the same.

My invention has relation to a new and original design for heel-plates for shoes; and it consists of a heel-plate of the configuration and ornamentation shown in the accompanying drawings, in which—

Figure 1 is a perspective view of the heel-plate, and Fig. 2 is a plan view of the same.

The leading features of my design consist in a heel-plate having a base portion 1, one 20 edge of which is curved from *a* to *b* on the arc of a small circle and from *b* to *c* on the arc of a greater circle, the other edge of which is curved inwardly from *d* to *e*, outwardly from *e* to *f*, and thence inwardly again on the

greater arc of a circle from *f* to *g*. The outer 25 edge of the base-plate has projecting upwardly therefrom a flange 2, which has a curvature corresponding to that of the outer edge of the base-piece. Holes 3, 4, and 5 are formed in the plate, as shown.

It will be observed that the base portion 1 has a curved or bulging portion *e*/*f* and that the flange 2 extends upward at right angles to said base portion, that the ends of the flange are vertical or squarely cut, that the 35 plan view of the design is somewhat in the form of a simitar, and that the flange is perforated near its ends and the base portion near the center.

What I claim is—

The design for a heel-plate for boots and shoes as herein shown and described.

In testimony whereof I hereunto affix my signature in presence of two witnesses.

WILLIAM BAYHOUSE.

Witnesses:

B. F. FRANCIS,
G. W. FLETCHER.
